WALL AND CEILING COVERING.

No.19,614.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,614, dated January 28, 1890.

Application filed December 26, 1889. Serial No. 335,045. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of ribbon spiral-shaped ornaments 1, which are connected together by spirals 2. The in-

tervening spaces are filled in with branching scrolls 3.

What I claim is—

15 The wall and ceiling covering herein shown and described, consisting of spiral-shaped ornaments connected by spirals, the spaces filled in with branching scrolls.

PAUL GROEBER.
